MERCHANDISE DISPLAY STAND

William S. Leath, Birmingham, Ala., assignor to EBSCO
Industries, Inc., a corporation of Delaware

Filed July 17, 1969, Ser. No. 18,248

Term of patent 14 years

Int. Cl. D6—01

U.S. CL. D80—9

FIG. 1 is an elevational view showing one side of my merchandise display stand, the side not shown being identical to the side shown;

FIG. 2 is a front elevational view thereof; and,

FIG. 3 is a top plan view thereof.

I claim:

The ornamental design for a merchandise display stand, as shown and described.
